R. B. POLLOCK,
DIRECTION INDICATOR,
APPLICATION FILED DEC. 30, 1918.

1,340,343.

Patented May 18, 1920.

UNITED STATES PATENT OFFICE.

ROBERT BOWERS POLLOCK, OF LOS ANGELES, CALIFORNIA.

DIRECTION-INDICATOR.

1,340,343.

Specification of Letters Patent. Patented May 18, 1920.

Application filed December 30, 1918. Serial No. 268,906.

To all whom it may concern:

Be it known that I, ROBERT B. POLLOCK, a citizen of the United States, residing at Los Angeles, in the county of Los Angeles and 5 State of California, have invented a new and useful Direction-Indicator, of which the following is a specification.

This invention relates to a device whereby 10 to the drivers of other vehicles the direction in which he is about to steer the vehicle, and also indicate when he is going to stop the vehicle.

An object of the invention is to produce a 15 device of this character of comparatively simple construction and one that is reliable in operation.

Another object is to cause display of the 20 visual signal by moving the operating member in either direction to indicate a turn in the same direction; and to cause display of both the visual signals by movement of the operating member still further in the same direction to indicate that the vehicle is about 25 to be brought to a stop.

Another object is to so construct the device that it will embody in its construction a tail light serving to illuminate the license 30 number of the vehicle, and also functioning to illuminate the visual signals at night.

Another object is to provide for sounding suitable audible signals coincidently with the displaying of the visual signals.

Another object is to effect the various 35 movements of the visual signals by a simple cam construction.

Other objects and advantages will appear in the subjoined detailed description.

The accompanying drawings illustrate the 40 invention.

Figure 1 is a front elevation of a direction indicator built in accordance with the provisions of this invention, the visual signaling members being in non-signaling position in 45 side of the casing.

Fig. 2 is an enlarged front elevation of the indicator, the front wall of the casing being omitted so as to expose to view the internal mechanism and one of the visual signals being shown in signaling position projecting from the casing.

Fig. 3 is an elevation similar to Fig. 2, excepting that both visual signals are displayed outside of the casing. In this view 55 is also diagrammatically indicated an auditory signal, a source of electric current, and

connections between the auditory signal, electric current source, casing and electric contacts in the casing.

Fig. 4 is an enlarged vertical section on line indicated by x^4-x^4 , Fig. 1.

Fig. 5 is an enlarged plan section on the curved line indicated by x^5-x^5 , Fig. 3.

There is provided a suitable casing indicated in general by the character 1. In the 65 instance shown the casing in profile is a trapezium. The rear wall 2 of the casing is intact and the front wall 3 is provided in its upper portion with an opening 4 through which projects a lamp 5 mounted in a socket 70 6 fastened to the rear wall 2. Below the level of the opening 4 the front wall is provided with a downwardly and forwardly slanting license number plate 7 which may be suitably fastened to brackets α projecting 75 forward from the sides of the casing. Directly in front of the opening 4 the casing forms a transversely extending hood 8 which may have its top slanted or curved downwardly from its middle toward its ends. 80 Immediately in front of the lamp 5 the hood 8 is provided with an opening 9, having a lens 10. Said lens may be of any desired color and will preferably be red so as to indicate danger. Thus the lamp 5 may be used 85 for the tail-lamp of the vehicle on which the indicator is placed.

The ends of the hood 8 are preferably open so that light rays from the lamp 5 can escape laterally from the hood for a reason 90 to appear hereinafter. The license number 11 is stamped or otherwise marked on the plate 7 and light rays from the lamp 5 will strike vertically downward through the bottom opening 12 of the hood upon the number 95 so that the number will be illuminated and may be easily read at night. The lamp 5 is shown in the drawings as an electric lamp, but it may be of any other type desired.

Pivoted at their lower ends near the lower 100 end of the casing 1 by pivots 13 is a pair of signal arms 14, 15 which extend upward almost to the top of the casing. The upper ends of the arms 14, 15 are provided with visual signals 16, 17 respectively which may 105 be in the form of flags and may be made of sheet metal or other suitable material. When the arms 14, 15 are in vertical positions the signals 16, 17 are housed within the casing and when the arms 14, 15 are 110 swung laterally toward the sides of the casing said signals project through openings

18 in the upper portions of the side walls of the casing.

The arms 14 and 15 are normally held in non-signaling position, and are moved into said positions from the signaling positions of Fig. 3 by springs 19 which engage the outer faces of the arms and which are fastened at their lower ends to the side walls of the casing. When the arms 14, 15 are in the signaling positions the springs 19 are compressed and tend to move said arms inward against stops 20 which may be in the form of pins projecting from the rear wall 2 of the casing into the path of travel of the arms so that said arms cannot move inward beyond predetermined positions.

The lower end of each of the arms 14, 15 is provided with a notch 21. The wall of each notch 21 has a curved upper portion 22 and a straight lower portion 23. The notch wall portion 23 forms a stop for an oscillatory member in the form of a cam 24, one end of said member forming a detent or arm 25 adapted to engage either one of the notches 21 and the periphery of said detent having a curved portion 26 to fit the curved wall portions 22. The wall portions 23 each form a stop to engage the arm 25 when said arm is in the appropriate notch 21. The opposite end of the member 24 forms an arm 27 adapted to engage either one of shoulders 28 on the arms 14, 15 when the detent enters the notch in the appropriate arm 14 or 15.

The member 24 is pivoted in the casing, the pivot being shown at 29. The pivot 29 may be in the form of a shaft to which the member 24 is fixed and may extend rearward of the casing through an opening 30 in the rear wall 2 thereof. Any suitable means may be provided for rocking the shaft 29, and in the drawings there is shown an arm 31 fixed to the rear end of the shaft. The arm 31 is adapted to be operated by any suitable means, not shown, which may extend within operating distance of the seat of the driver of the vehicle to which the indicator is attached. The notch 21 of either of the arms 14, 15 is so positioned relative to the shoulder 28 of the other of said arms that the cam 24 does not come into engagement with the shoulder 28 of one of the arms 14, 15 until the cam has been turned sufficiently far to move the other of said arms outward to the signaling position, and as the cam enters the notch of said other arm the arm 27 of the cam rides against the shoulder 28 of the first named arm and causes said arm to swing outward to signaling position. This is clearly shown in Fig. 3.

It is to be noted that when the lamp 5 is burning some of the light rays therefrom strike laterally through the open ends of the hood 8 upon the signal 16 or 17 or both,

as the case may be, when said signal or signals are in display positions.

The back wall 2 of the casing, if desired, may be provided with a recess 32 in which is inserted insulation 33. On the insulation 76 33 are electric contacts 34, 35, 36 which are connected to one another by a conductor strip *c* as clearly shown in Fig. 5. Between the contacts 34, 35 and between the contacts 35, 36 is insulation 38, said insulations having their outer faces flush with the outer faces of said contacts. In the arm 15 and projecting rearwardly therefrom is a contact 39 adapted to engage the contact 34 as the arm 15 moves from non-signaling position to signaling position, there being a spring 40 to yieldingly hold the contact 39 outward. In the arm 14 and projecting rearwardly therefrom is a contact 41 adapted to successively engage the contacts 35, 36 as the arm 14 moves from non-signaling to signaling position, there being a spring 42 to yieldingly hold the contact 41 outward. The strip *c* is connected with an electric conductor 43 passing through a bushing 44 in the rear wall 2 of the casing. The conductor 43 is connected with the coil 45 of an auditory signal 46 and said coil is connected by a conductor 47 to a source 48 of electric current which in turn is connected by a conductor 49 to the casing so that the electric current will flow through the arms 15, 14 to their contacts when said contacts respectively engage the contacts 35, 36 and contact 34.

From the foregoing it is clear that, when the arm 15 swings outward, the auditory signal 46 will sound or toot once; that, when the arm 14 swings outward, the auditory signal will toot twice; and that, when both arms 14, 15 are swung outward, the auditory signal will toot thrice.

In practice, the operation of the device is as follows:

Assuming that the above described direction indicator is suitably mounted on the rear end of a vehicle with the front wall 3 facing rearward and that the arms 14, 15 are in non-signaling positions, as in Fig. 1, if the driver of the vehicle desires to turn the vehicle to the right he will cause the arm 31 to turn to the right to a degree sufficient to move the arm 15 and its signal 17 and the cam 24 to positions shown in Fig. 2, thus indicating to drivers in the rear that a right turn is about to be executed. If the driver desires to turn to the left he will cause the arm 31 to turn to the left to a degree sufficient to move the arm 14 to signaling position the same as described above for the arm 15. In indicating either the right or left turn the cam 24 does not enter the notch 21.

If the driver desires to stop he may indicate his desire to drivers in the rear by

turning the arm 31 to a greater degree than above described, in either direction, so as to cause the cam to bear against the appropriate shoulder 28. For instance, in Fig. 3 5 the cam has been turned from the position shown in Fig. 2 to a degree sufficient to enter the cam in the slot 21 of the arm 15 and cause the cam to kick out the arm 14 to signaling position, thus causing display 10 of both visual signals.

When the right turn is indicated visually it is evident that one toot or sounding of the auditory signal 46 will be given; that indicating visually a left turn will cause 15 two soundings of the auditory signal; and that indicating visually a stop will result in three soundings of the auditory signal to be given.

From the above description of the cam 20 device of the invention it is clear that the cam 24 is, in effect, a lost motion connection between the shaft 29 and the arms 14, 15 so that when either of the arms 14, 15 has been moved to signaling position said arm 25 will remain stationary while the other arm is being moved to signaling position. It is also seen that there are provided means to move either signal from non-signaling position to signaling position independently of one another and thereafter to move into signaling position the signal not first moved while the signal first moved is in the signaling 30 position.

From the foregoing it is apparent that 35 the indicator is of comparatively simple construction and that the signals "Right turn" "Left turn" and "Stop" are readily given by the driver by simply operating one control member to the right, and left 40 to intermediate positions and to the right or left to extreme positions.

It is to be understood that the invention in its broader phases is not limited to the exact details of construction described 45 above and shown in the drawings, but that such changes and modifications are included as lie within the spirit and scope of the invention as expressed in the appended claims.

Though the auditory signal 46 is shown 50 in Fig. 3 of the drawings as being in the form of an electrically operated horn and the sound emitted by it has been termed a "Toot," it is understood that said signal 55 may be a bell or any other sound-producing device and that the term "Toot" defines any audible sound produced by said signal.

I claim:

1. A direction indicator comprising visual 60 signals, means to move either signal from non-signaling position to signaling position independently of one another and thereafter to move into signaling position the signal not first moved while the signal 65 first moved is in the signaling position, and

means operative when one of the signals is being moved to sound one toot and operative when the other signal is being moved to sound two toots.

2. A direction indicator comprising visual 70 signals, and means including a lost motion connection to move either signal from non-signaling position to signaling position independently of one another and thereafter to move into signaling position 75 the signal not first moved while the signal first moved is in the signaling position.

3. A direction indicator comprising movably mounted arms, visual signals on the arms respectively, and a rotatively mounted 80 cam adapted to separately or simultaneously engage and move the arms.

4. A direction indicator comprising movably mounted arms, visual signals on the arms respectively, a shaft, a member on the 85 shaft having a detent to engage either of the arms when the shaft is turned, there being notches in the arms to receive the detent when the detent has moved either arm to a certain position, and means on the member 90 adapted to engage and move the other arm when the detent is moving in the notch.

5. A direction indicator comprising visual 95 signals, a single control member, means operative by moving the control member into different positions to move either signal from non-signaling position to signaling position independently of one another and thereafter to move into signaling position the signal not 100 first moved while the signal first moved is in the signaling position, and means operative by moving of one of the signals to make one auditory signal and operative by moving of the other signal to make a different signal.

6. A direction indicator comprising visual 105 signals, a single control member, means operative by moving the control member into different positions to display the signals independently and simultaneously, and means 110 operative by the first named means to produce different auditory signals for the independent and simultaneous displays of the visual signals.

7. A direction indicator comprising visual 115 signals, a single control member, means operative by moving the control member into different positions to display the signals independently and simultaneously, and means operative by the first named means to produce different auditory signals for the display of each visual signal independently and for the display of the visual signals simultaneously.

8. A direction indicator comprising a casing, arms pivoted to the casing and provided with notches respectively, springs in the casing yieldingly holding the arms toward one another, signals on the arms adapted to be displayed outside of the casing 125 130

when the arms are swung outward, a cam pivoted in the casing between the arms and having a portion adapted to engage one of the arms adjacent the notch thereof when the cam is turned to a certain degree in either direction and adapted to engage the notch thereof when the cam is turned to a greater degree, the notch permitting movement of the cam independently of the arm having said notch and the cam having another portion adapted to be free from the arms when the first named portion thereof is in engagement with the first named arm, said second named cam portion being adapted to engage the other arm when the first named cam portion is moving in the notch of the first named arm, and means to rock the cam.

9. A direction indicator comprising visual signals, means to display the signals independently and together, said means including but a single control member, and means

operative by the display of one visual signal to make an auditory signal and operative by the display of the other visual signal to make a different auditory signal and operative by the display of both signals to make a still different auditory signal. 25

10. A direction indicator comprising visual signals, means to display the signals independently and together, and means operative by the display of one visual signal to make an auditory signal and operative by the display of the other visual signal to make a different auditory signal and operative by the display of both signals to make a still different auditory signal. 30 35

Signed at Los Angeles, Calif., this 23d day of December, 1918.
